UNITED STATES PATENT OFFICE.

JOHN W. DWYER, OF PHILADELPHIA, PENNSYLVANIA.

DESIGN FOR A CHILD'S ROCKER.

51,806.

Specification for Design.

Patented Feb. 26, 1918.

Application filed December 21, 1917. Serial No. 208,329. Term of patent 3½ years.

To all whom it may concern:

Be it known that I, JOHN W. DWYER, a citizen of the United States, residing in the city and county of Philadelphia, State of Pennsylvania, have invented a new, original, and ornamental Design for a Child's Rocker, of which the following is a specification, reference being had to the accompanying drawing, forming part thereof.

The figure is a perspective view of a child's rocker showing my new design.

I claim:—

The ornamental design for a child's rocker as shown.

JOHN W. DWYER.
